(57) **CLAIM**

The ornamental design for a template for making bags, as shown and described.

DESCRIPTION

The patent or application file contains at least one drawing executed in color. Copies of this patent or patent application publication with color drawing(s) will be provided by the Office upon request and payment of the necessary fee.

FIG. 1 is a perspective view of a template for making bags in accordance with my invention thereof;

FIG. 2 is a front view thereof;

FIG. 3 is a rear view thereof;

FIG. 4 is a top plan view thereof;

FIG. 5 is a bottom view thereof;

FIG. 6 is a left side view thereof;

FIG. 7 is a right side view thereof;

FIG. 8 is a perspective view of a template for making bags according to a second embodiment of my new design, a top plan view, bottom view, left side view and right side view being identical to FIGS. 4-7, respectively;

FIG. 9 is a front view of the template according to the second embodiment; and,

FIG. 10 is a rear view of the template according to the second embodiment.
